UNITED STATES PATENT OFFICE.

JAMES C. FRENCH, OF KENOSHA, WISCONSIN, ASSIGNOR TO FREDERICK C. AUSTIN,
OF CHICAGO, ILLINOIS.

OSCILLATING TRENCH-MACHINE.

1,239,897.

Specification of Letters Patent. Patented Sept. 11, 1917.

Application filed March 22, 1915. Serial No. 16,302.

To all whom it may concern:

Be it known that I, JAMES C. FRENCH, a citizen of the United States of America, and resident of Kenosha, Kenosha county, Wisconsin, 5 510 Exchange street, have invented a certain new and useful Improvement in Oscillating Trench-Machines, of which the following is a specification.

My invention relates to trenching machines of that kind in which an endless series of digging buckets is arranged to operate continuously in the ground and thereby cut a trench while the machine moves slowly ahead in the direction desired 15 for the trench.

The object of my invention is to provide a machine of this character in which provision is made for oscillating the body upon which the bucket frame or beam and the 20 driving engine and other elements are mounted to swing the said digging buckets back and forth sidewise and thereby enable the machine to cut a much wider trench than is ordinarily possible in a machine of this 25 kind having only a forward movement during the operation of the buckets.

It is also an object to provide certain details and features of construction and combinations tending to increase the general 30 efficiency and desirability of an oscillating trench machine of this particular character.

To these and other useful ends my invention consists in matters hereinafter set forth and claimed.

35 In the accompanying drawings,

Figure 1 is a side elevation of an oscillating trench machine embodying the principles of my invention.

40 Fig. 2 is a plan of said machine, showing the oscillating movement thereof in dotted lines.

45 Fig. 3 is an enlarged plan of the reversing gear mechanism by which the upper body or turntable is automatically oscillated about a vertical axis during the operation of the machine.

50 Fig. 4 is a detail plan view, on a still larger scale, of the automatic tripping devices by which the clutches are operated to reverse the oscillation of the turn-table.

As thus illustrated, my invention comprises a lower body frame A supported on front steering wheels a and rear traction de-

vices B, the latter being what are ordinarily known as caterpillars, or of any other suitable character. The main body frame or turn-table C is provided with wheels c that travel in curved tracks D mounted on the lower body frame, whereby the said turn-table oscillates about a vertical axis at d 55 while the machine is in operation, as will hereinafter more fully appear. At its rear end the turn-table C is provided with a frame x upon which is mounted a drive-shaft E extending transversely of the machine and supported in suitable bearings thereon. An engine F is supported upon the forward portion of the turn-table C and connected by a belt f with a wheel G, the latter being mounted on a shaft g suitably 60 supported on the upper body frame. A sprocket chain H and suitable sprockets are employed as the medium of power transmitting connection between the shaft E and the shaft g, it being understood that suitable 65 clutches may be employed for controlling this driving connection between the engine and the shaft E, and the invention is not limited to any particular arrangement for 70 this purpose. It will also be understood 75 that gearing of any suitable character can be employed for connecting the engine with the caterpillars B, the power transmitting connection in this case preferably including, however, a vertical shaft extending downward at d, whereby the oscillation of the 80 turn-table does not interfere with the transmission of power to the caterpillars.

The swinging digging beam or bucket frame I is suitably supported at its upper 85 end on the shaft E, and is arranged at the rear end of the machine, this shaft E being supported by the frames e (one at each side of the machine) which extend rearward at opposite sides of said beam, so that the beam 90 is held or maintained in line with the body C when the latter swings the beam from one side to the other. The digging buckets J are suitably supported on sprocket chains j 95 which travel over upper and lower sprockets K and L at the upper and lower ends of the digging beam, the sprockets K being suitably secured and spaced apart on the shaft E in the usual and well known manner. The idlers M are mounted on supplemental 100 frames m secured on the back of the dig- 105

ging beam I, and are arranged in position to support the sprocket chains *j* and cause the descending buckets to have a vertical path of travel from the surface of the ground to the bottom of the trench. The ascending buckets, of course, have an inclined path of travel, when the digging beam I is in normal operating position. Said buckets are secured to the chains only at their forward ends, whereby each bucket tilts outward as it starts to pass over the shaft E, thereby discharging the contents or load upon the transversely arranged conveyer N arranged at the rear end of the machine in the usual well known manner. A supplemental frame O is rigidly secured to the upper portion of the digging beam I, and the upper end of this frame is suitably connected with a vertically disposed screw P, whereby rotation of this screw will serve to tilt the digging beam I about the horizontal axis provided at its upper end. In this way, the beam I and the buckets J can be swung upward to a position above ground in the usual and well known manner. Any suitable means can be employed for rotating the screw P, as for example by gear connecting its lower end with the shaft *g*, and by providing suitable clutches for controlling the transmission thus provided and thereby reversing the rotation of the screw P at will. The buckets K are in operation at the same time that the caterpillars B are operated to move the machine slowly forward. This, it will be understood, results in the cutting of a trench of substantially the same width as the buckets.

In order, however, that the machine may be employed for making a trench of greater width than the buckets, the body C or turn-table is oscillated during the operation of the buckets, and in this way the said buckets are moved back and forth sidewise, during the forward movement of the machine, with the result that the trench is widened to the desired extent. For this purpose the buckets may be constructed and arranged to cut on the sides of the trench, as well as straight ahead, and at such time it will be observed that the descending buckets after passing the idlers M operate on the sides of the trench in a manner to leave the latter exactly vertical, or substantially so, after the machine has traveled forward. The machine may, however, have any suitable arrangement for preventing the angle of the bucket-frame or beam I from leaving the trench with overhanging sides. Any suitable means can be employed for oscillating the turn-table C and the invention is not limited to any particular mechanism for so doing.

As a matter of further and special improvement, however, worm gears Q and R may be employed for engaging curved racks *q* and *r* secured to the underside of the turn-

table, said gears being mounted in suitable bearings on the lower body frame. A longitudinal shaft S is connected at its opposite ends by a bevel gearing *s* with the said worm gears. The reversing bevel gears T and *t* are loose on said shaft and are rotated in opposite directions by bevel gear *b* suitably connected to be driven from the axis *d* or center about which the turn-table oscillates while in operation. Clutches 1 and 2, 70 of any suitable character, are employed for connecting the bevel gears P and *p*, respectively, with shaft S, whereby the latter may be rotated in either direction, depending upon which clutch is open and which clutch 80 is closed. The said clutches are suitably connected with a horizontally disposed lever arm, U, suitably supported on the lower body-frame, the arrangement being such that vibration of this lever arm from side to 85 side will open one clutch and close the other, and vice versa, thereby causing the shaft S to rotate first in one direction and then in the other. In order that the oscillating turn-table may itself accomplish this 90 automatic reversal of the shaft S, the arm U is pivotally connected with a rod *u* having its ends pivotally connected, respectively, with the bell cranks V and W, the latter being suitably pivoted on the lower body 95 frame. A compression spring telescoping connection *v* is provided in the rod *u* between the bell crank V and the arm U, and a similar connection *w* is provided between the said arm and the bell crank W at the 100 other end. The catches X and Y are suitably pivoted on the lower body frame and arranged to alternately engage the locking end portion Z of the lever arm. A rod 3 connects the catch X with the bell crank V, 105 and a similar rod 4 connects the catch Y with the bell crank W, and these rods each have a telescoping or lost motion connection 5 suitably incorporated in the same at points between the ends thereof. Pins 6 and 7, see 110 Fig. 4, are mounted on the under-side of the turn-table and disposed in position to engage the arms 8 and 9, respectively, of the two bell cranks. As shown, the pin 7 has approached the bell crank W, thereby compressing the spring connection *w* at a time when the portion Z was in locking engagement with the catch Y, it being understood that the telescoping connection 5 of the rod 4 permitted the bell crank W to compress the 115 spring connection *w* without disengaging the catch Y from the portion Z, and without releasing the latter. The final movement of the bell crank W, when engaged by the pin 7, serves to disengage the catch Y, inasmuch as the lost motion of the connection 5 in the rod 4 is taken up a little before the said bell crank reaches the limit of its motion. As soon as the catch Y is disengaged 120 from the portion Z, the compressed spring 125 130

w then quickly shifts the rod U to the left, thereby operating the lever arm U and causing a reversal of the clutches 1 and 2 in a manner to reverse the rotation of the shaft 5 S and thereby reverse the oscillation of the turn-table. When the said turn-table reaches the limit of its motion in the other direction, thereby causing the pin 6 to operate the bell crank V, the spring connection v is compressed and the catch X is disengaged from the portion Z, thereby automatically shifting the rod u to the right, causing the arm U to again occupy the position shown in dotted lines. This again reverses the 10 clutches 1 and 2 and causes a corresponding reversal of the oscillation of the turn-table. Thus, and in this way, the oscillating movement of the turn-table upon which the engine F, digging beam I, and other operating 15 elements, are all mounted in the manner previously described, serves to automatically reverse the power transmitting connections by which the engine operates the turn-table, whereby this oscillating movement will continue during the forward movement of the 20 machine. The previously described widening of the trench is thus accomplished automatically.

With the foregoing construction, it will 25 be seen that the buckets oscillate about a vertical axis which is disposed a distance in advance of the digging beam, so that all of the axes of movement of the said digging beam are in advance of the excavating operation. The horizontal axis E is ahead of the 30 buckets which are in action, and the vertical axis provided by the turn-table is some distance ahead of this horizontal axis, whereby the buckets are movable up and down and 35 sideways about axes which are ahead of the digging operation, and which remain so as the machine moves forward. In this way, the upwardly traveling buckets operate on the breast of the excavation, while the downwardly traveling buckets operate on the 40 sides of the trench, in the manner shown and described.

Thus the trench is much wider than the 45 buckets, and the descending buckets cut away the dirt first at one side of the trench and then at the other.

However, I do not, of course, limit myself 50 to the exact construction shown and described.

55 What I claim as my invention is:

1. An excavator for making trenches or ditches, comprising an endless series of digging buckets, an inclined frame for supporting said buckets in position to operate in 55 the ground, mechanism for operating said bucket, means for propelling the machine forward during the operation of the buckets, in the direction desired for the trench or ditch, a power-plant to operate said mechanism and means, and instrumentalities in-

cluding a turn-table upon which said frame and mechanism and power-plant are supported for oscillating movement about a vertical axis disposed a distance ahead of the digging point to give the buckets in 70 action a back-and-forth sidewise motion behind said axis, so that the trench will be wider than the buckets, and whereby the descending buckets cut away the dirt first at one side of the trench and then at the other, 75 said excavator having means to insure operation of said buckets in such manner that the angle of said frame will not leave the trench with overhanging sides.

2. An excavator comprising an endless 80 series of digging buckets, a frame for supporting said buckets in position to operate in the ground, mechanism for operating said buckets, means for propelling the machine forward during the operation of the buckets, 85 and instrumentalities including a turn-table upon which said frame and mechanism are supported for oscillating movement about a vertical axis disposed a distance ahead of the digging point to give the buckets in action 90 a back and forth sidewise motion behind said axis, so that the trench will be wider than the buckets, and whereby the descending buckets cut away the dirt first at one side of the trench and then at the other, said excavator having means to insure operation of 95 said buckets in such manner that the angle of said frame will not leave the trench with overhanging sides, said frame being mounted to swing up and down about a horizontal 100 axis extending transversely of the machine.

3. An excavator comprising an endless 105 series of digging buckets, a frame for supporting said buckets in position to operate in the ground, mechanism for operating said buckets, means for propelling the machine forward during the operation of the buckets, and instrumentalities including a turn-table upon which said frame and mechanism are supported for oscillating movement about a 110 vertical axis disposed a distance ahead of the digging point to give the buckets in action a back and forth sidewise motion behind said axis, so that the trench will be wider than the buckets, and whereby the descending buckets cut away the dirt first at one side of the trench and then at the other, 115 said excavator having means to insure operation of said buckets in such manner that the angle of said frame will not leave the 120 trench with overhanging sides, devices on said turn-table to raise and lower said frame, and an engine mounted on said turn-table and connected for operating said mechanism and means and devices.

4. An excavator comprising an endless 125 series of digging buckets, a frame for supporting said buckets in position to operate in the ground, mechanism for operating said buckets, means for propelling the machine 130

4
forward during the operation of the buckets, and instrumentalities including a turn-table upon which said frame and mechanism are supported for oscillating movement about a vertical axis disposed a distance ahead of the digging point to give the buckets in action a back and forth sidewise motion behind said axis, said frame having means for causing the descending buckets to have a vertical path of travel in the ground, thereby to prevent overhang at the side of the trench or ditch.

5. An excavator comprising an endless series of digging buckets, a frame for supporting said buckets in position to operate in the ground, mechanism for operating said buckets, means for propelling the machine forward during the operation of the buckets, and instrumentalities including a turn-table upon which said frame and mechanism are supported for oscillating movement about a vertical axis disposed a distance ahead of the digging point to give the buckets in action a back and forth sidewise motion behind said axis, said buckets being arranged to form a trench, and means for preventing the sidewise motion of the buckets from under-cutting the sides of the trench.

6. An excavator comprising an endless series of digging buckets, a frame for supporting said buckets in position to operate in the ground, mechanism for operating said buckets, means for propelling the machine forward during the operation of the buckets, and instrumentalities including a turn-table upon which said frame and mechanism are supported for oscillating movement about a vertical axis disposed a distance ahead of the digging point to give the buckets in action a back and forth sidewise motion behind said axis, so that the trench will be wider than the buckets, and whereby the descending buckets cut away the dirt first at one side of the trench and then at the other, said excavator having means to insure operation of said buckets in such manner that the angle of said frame will not leave the trench with overhanging sides, gearing for operating the turn-table, and means controlled by the oscillation of the turn-table to automatically reverse said gearing.

7. An excavator comprising an endless series of digging buckets, a frame for supporting said buckets in position to operate in the ground, mechanism for operating said buckets, means for propelling the machine forward during the operation of the buckets, and instrumentalities including a turn-table upon which said frame and mechanism are supported for oscillating movement about a vertical axis disposed a distance ahead of the digging point to give the buckets in action a back and forth sidewise motion behind said axis, so that the trench will be wider than the buckets, and whereby the descend-

ing buckets cut away the dirt first at one side of the trench and then at the other, said excavator having means to insure operation of said buckets in such manner that the angle of said frame will not leave the trench with overhanging sides, said mechanism including sprocket chains to which said buckets are secured, upper and lower sprockets for said chains, the upper sprockets having a shaft forming a horizontal axis of pivotal adjustment for said frame.

8. An excavator comprising an endless series of digging buckets, a frame for supporting said buckets in position to operate in the ground, mechanism for operating said buckets, means for propelling the machine forward during the operation of the buckets, and instrumentalities including a turn-table upon which said frame and mechanism are supported for oscillating movement about a vertical axis disposed a distance ahead of the digging point to give the buckets in action a back and forth sidewise motion behind said axis, so that the trench will be wider than the buckets, and whereby the descending buckets cut away the dirt first at one side of the trench and then at the other, said excavator having means to insure operation of said buckets in such manner that the angle of said frame will not leave the trench with overhanging sides, said buckets having a dumping position at the highest portion of their path of travel, and a conveyer disposed below said position and supported on said turn-table.

9. An excavator comprising an endless series of dumping buckets, a frame for supporting said buckets in position to operate in the ground, mechanism for operating said buckets, means for propelling the machine forward during the operation of the buckets, and instrumentalities including a turn-table upon which said frame and mechanism are supported for oscillating movement about a vertical axis disposed a distance ahead of the digging point to give the buckets in action a back and forth sidewise motion behind said axis, said buckets having a triangular path of travel, the triangle being disposed with the long side thereof inclined forward, the lower rear side of this triangle being vertical, and said buckets traveling up the inclined side and down the vertical side.

10. An excavator comprising an endless series of digging buckets, a frame for supporting said buckets in position to operate in the ground, mechanism for operating said buckets, means for propelling the machine forward during the operation of the buckets, and instrumentalities including a turn-table upon which said frame and mechanism are supported for oscillating movement about a vertical axis disposed a distance ahead of the digging point to give the buckets in action a back and forth sidewise motion be-

hind said axis, so that the trench will be wider than the buckets, and whereby the descending buckets cut away the dirt first at one side of the trench and then at the other, 5 said excavator having means to insure operation of said buckets in such manner that the angle of said frame will not leave the trench with overhanging sides, and adjustable means for holding said frame in fixed

relation to said turn-table during the oscillation thereof.

Signed by me at Chicago, Illinois, this 20th day of March 1915.

JAMES C. FRENCH.
